UNITED STATES PATENT OFFICE.

LOUIS STREBEL, OF NEW YORK, N. Y.

EXPLOSIVE ENGINE.

1,411,536.

Specification of Letters Patent.

Patented Apr. 4, 1922.

Application filed May 17, 1919. Serial No. 297,783.

To all whom it may concern:

Be it known that I, LOUIS STREBEL, a citizen of the United States, and resident of New York, in the county of New York and 5 State of New York, have invented certain new and useful Improvements in Explosive Engines, of which the following is a specification.

The invention relates essentially to multi-cylinder four cycle engines, of the kind in which a tubular rotary valve controls the intake of the combustible and also the exhaust of the products of combustion from the cylinders.

One of the objects of the present invention is to provide the valve with duplex intake and exhaust ports to successively register with the port leading to each cylinder so that the valve can be revolved very slowly 10 to obviate breakage of the parts while the crank shaft is running at a high rate of speed.

Another object of the invention is to provide a cylindrical valve of smaller diameter 15 than the bore of the casing so as to compensate for the expansion and contraction caused by the heat generated from the explosion.

Another object of the invention is to equip 20 the valve with devices for forcing it against the bore in order to eliminate leakage of the combustible.

The invention also includes means connected to the device for automatically lubricating the valve.

The invention resides in the novel combinations hereinafter described and claimed, reference being made to the accompanying drawings in which:—

40 Figure 1 represents a vertical longitudinal section of an engine embodying this invention.

Figure 2 is a sectional end view showing the plunger.

45 Figure 3 is a horizontal longitudinal section of the valve and its casing.

Figure 4 is a vertical longitudinal section of the valve.

50 Figure 5 is a transverse section taken along the line 5—5 of Figure 4.

Figure 6 is a similar section taken along the line 6—6 of the same.

55 Figure 7 is a similar section taken along the line 7—7 of the same, showing the valve and its casing.

Figure 8 is a similar section taken along the line 8—8 of the same.

Figure 9 is a similar section taken along the line 9—9 of the same.

Figure 10 is a diagram of the cylinders 60 showing the successive cycles of the engine.

Figure 11 is a diagram of the valve.

In the drawings is shown an explosive engine or motor having a series of cylinders 12 coupled together, each provided with a piston 13 made to reciprocate in the cylinder by the explosion of a combustible. The pistons are connected by means of rods 14 to the cranks 15 formed on a driving shaft 16 mounted to rotate in bearing 17 extending 65 from the lower portions of the cylinders. A water jacket 18 is provided for cooling the cylinder as is well known.

Surmounting the cylinders is located a casing 19 having a longitudinal bore 20 open 75 at each end. A water jacket 21 partly surrounding the bore is made to cool the casing. The casing is equipped with a plurality of ports 22 for connecting the interior of each cylinder 12 with the bore 20 of the casing, 80 the function of which will be hereinafter described.

In the center of the casing 19 is located a compartment 23 partly surrounding the bore, and a pipe connection 24 conducts the 85 fuel from a carburetor into the compartment where the fuel is heated before it is distributed into the cylinders.

A cylindrical tubular valve 25 for controlling the distribution of the combustible 90 is loosely arranged in the bore of the casing and front and rear covers 26 secured to each end of the casing eliminate longitudinal movement of the valve. Duplex intake ports 27 disposed in the central portion 95 of the valve conduct the combustible from the compartment 23 into the valve. A series of duplex inlet ports 28 and exhaust ports 29 are formed in the circumference of the valve to coact at predetermined times 100 with the ports 22 in the casing.

A number of winding partitions 30 in the valve divide it into duplex passage-ways 31 and chambers 32, the passage-ways being adapted to lead off the products of combustion, while the chambers constitute the intake for distributing the combustible mixture to the cylinders. A pipe 33 fitted to the rear cover 26 and communicating with the passages will conduct the products of 110

combustion from the cylinder when one or the other of the exhaust ports 29 is in register with a cylinder port.

- The forward end of the valve is equipped 5 with a journal 34 passing through a hole in the forward cover 26 and on its outer end is mounted a worm gear 35 meshing with a worm or tangent 36 fixed to one end of a vertical shaft 37 extending downward. 10 The other end of the vertical shaft carries a small worm 38 engaged by a worm gear 39 on the forward end of the crank shaft. The rotation of the vertical shaft is uniform with the crank shaft but the upper 15 worm and gear have teeth of different pitch and the gear 35 being considerably larger than the worm it will revolve the valve in the ratio of one revolution to four revolutions of the crank shaft. In this arrangement each stroke of the piston will transmit 20 one-eighth of a revolution to the valve. In other words two revolutions of the crank shaft will complete four cycles and transmit one-half a revolution to the valve. 25 A timer 40 of suitable construction is interposed between the worm gear 35 and the forward cover and it can be connected to operate in the usual manner.

As indicated in Figures 3 and 4 the chambers 32 in the valve receive the combustible from the compartment 23 through the medium of the central ports 27 when adjacent to the compartment. Hence when one of the inlet ports 28 register with a port 22 30 leading into a cylinder the combustible will flow into that particular cylinder and be exploded. The ports are timed to permit the first cylinder to explode the combustible, the second to compress, the third to exhaust, 35 and the fourth to intake the combustible mixture. Each cylinder has a single port leading to the upper part of the cylinder and cooperating with the valve to at times intake and at other times perform the functions of exhausting the products of combustion after the explosion. It will be 40 readily understood that when one of the exhaust ports is in alignment with one of the cylinder ports the products will flow 45 through one of the duplex passages 31 and out of the conduit 33 at the end of the valve.

As indicated in Figure 10 the four figures from top to bottom illustrate the four successive strokes of the engine. The position 50 of the various pistons and their relation to each other when the front cylinder is about to fire is shown in the upper figure. The pistons move downward during the explosion and intake strokes and they move upward during the compression and exhaust strokes. In this arrangement, the front cylinder fires first, then the second cylinder, then the fourth cylinder, and lastly the third cylinder. The four operations of the cycle 55 namely, suction, compression, explosion and

exhaust are repeated in regular order in each of the four cylinders according to the firing order. When the first piston is at the top of its stroke with the fuel above it 60 fully compressed and ready for ignition, the second piston is at the bottom of the suction stroke just at the beginning of its compression stroke and the valve 25 cooperating with the ports in both cylinders is closed. When the piston in the third cylinder starts moving up on its exhaust stroke, it will force the products of combustion out of the cylinder through one of the passageways of the valve. The piston in the fourth cylinder is then moving downward and 65 when one of the intake passageways is adjacent to the port 22 it permits a charge of gas to be drawn into the cylinder from the carburetor.

By having the valve loosely mounted in 70 the bore of the cylinder it compensates for the expansion and contraction of the valve produced by the heat generated by the explosion. The valve can thus revolve freely 75 whether it is expanded by the heat or contracted when it cools off. In order to at all times press the valve against the bore 80 a pair of plungers or buffers 41 are provided as indicated in Figures 1 and 2. 85 Each plunger is slidably mounted in a sleeve 42 projecting upwardly from the cylinder and it includes a stem 43 having a channel 44 with a socket 45 above the channel. The lower end of the plunger carries a counter-sunk felt or asbestos pad or 90 wick 46 communicating with the channel. A coiled spring 47 presses the plunger 95 against the periphery of the valve, thus forcing the valve onto its seat to effectively 100 eliminate leakage of the combustible between the joints. The upper portion of the spring strikes onto the inner surface of a nut 48 having a central opening for the stem to slide, and the nut can be adjusted 105 to expand and compress the spring thereby 110 transmitting more or less pressure onto the plunger.

A vertically positioned oil supply pipe 49 telescopes into the socket of the plunger. The socket of the plunger forms a sliding 115 connection permitting the pipe to remain stationary while the stem and its plunger moves radially against the action of the spring to take up the expansion and contractions of the valve. A horizontal pipe 50 having an oil supply 51 such as a cup, not 120 shown, will lubricate the valve by conducting the oil through the channels 44 in the plungers. Vertical branch pipes 52 connected to the oil pipe 50 lead to a pad or 125 wick 53 embedded in a groove in the side of the cylinder extending the length of the bore, best seen in Figures 2 and 3. By having the latter pad extend the entire 130 length of the valve it will contact with its

entire surface to keep all that portion of the valve in the bore thoroughly lubricated.

It should be noted that the valve is given one-half a revolution to four strokes and 5 the valve intakes and exhausts once during the cycles. There are two intake and two exhaust ports circumferentially in a line with each other made to cooperate with the single port leading into the cylinder so that 10 at a complete revolution of the valve each piston has made eight strokes while the valve has governed the admission and expulsion twice.

I claim:

15 1. An explosive engine comprising a plurality of cylinders each having a port to alternately intake and exhaust, a casing having an inlet, a tubular rotary valve with a pair of intake ports to at times register 20 with the inlet, dual intake and exhaust passages in the valve for conducting the combustible, duplex peripheral intake and exhaust ports continuous with the passages to individually register with a port in a cylinder and a port in the casing coacting with the exhaust 25 passages.

2. An explosive engine comprising a plurality of cylinders each having a port to alternately intake and exhaust, a casing 30 having an inlet, a tubular rotary valve

with a pair of intake ports to at times register with the inlet, winding dual intake and exhaust passages in the valve independent of each other to conduct a combustible, duplex peripheral intake and exhaust ports 35 continuous with the passages to individually register with a port in a cylinder, and a port in the casing coacting with the exhaust passages.

3. An explosive engine comprising a casing having multi-cylinders, a rotary cylindrical valve controlling the intake and exhaust arranged in a bore of the casing, a plunger cooperating with the valve to press it against the bore of the casing, and means 40 slidably connected to the plunger for supplying oil to lubricate the valve.

4. An explosive engine comprising a casing having multi-cylinders, a rotary cylindrical valve controlling the intake and exhaust arranged in a bore of the casing, a plunger cooperating with the valve to press it against the bore of the casing, a channel 50 in the plunger for supplying oil to lubricate the valve, and a reservoir movably connected 55 to the plunger for feeding the oil.

Signed at New York in the county of New York and State of New York this 16th day of May A. D. 1919.

LOUIS STREBEL.
